UNITED STATES PATENT OFFICE.

HANFORD R. MILES, OF UPLAND, INDIANA.

MOLDING-BIT.

SPECIFICATION forming part of Letters Patent No. 768,234, dated August 23, 1904.

Application filed June 10, 1903. Serial No. 160,923. (No model.)

To all whom it may concern:

Be it known that I, HANFORD R. MILES, a citizen of the United States, residing at Upland, in the county of Grant and State of Indiana, have invented a new and useful Mold-
5 ing-Bit, of which the following is a specifica-
tion.

My invention is an improvement in mold-
ing-bits, and has for its object to provide a bit
10 of this kind which can be used on any square-
head machine, one which can be sharpened
without the cut of the mold being changed
and in which the bit is so constructed as to
make a clean shear cut, as in a dado-bit, where-
15 by it is adapted to cut across the grain, and
being firmly fastened to the head is also en-
abled to resist the lead of the grain and cut
with it.

With these objects in view my invention
20 consists in the novel features of construction
and combination hereinafter described, partic-
ularly pointed out in the claims, and shown
in the accompanying drawings, in which—

Figure 1 is a perspective view of one mem-
25 ber of the door-bit. Fig. 2 is a section through
a portion of a door-stile, one side being shown
as cut and the cut to be made by the other
member of the bit being shown in dotted lines.
Fig. 3 is a front edge view of the bit.

30 In the construction of these bits I employ
the flat metal body A, bifurcated at one end
forming the two parallel shanks A'. These
bits carry a narrow forwardly-extending
prong B, one of the sides of said prong being
35 in alinement with the outer side of one of the
shanks, the prong being beveled, as shown at
B', to form a cutting edge transverse to the
longitudinal axis of the prong. On the same

side of the plate A as the prong B is an inte-
gral cutting-blade C, curved outwardly and 40
laterally from the plate A in a compound
curve, the forward portion of the blade C be-
ing coextensive with the rear portion of the
prong B. The blade C has a cutting edge on
its forward edge, as shown at C'. These bits 45
are used in pairs, but one member of the pair
being shown in the drawings. When in op-
erative position, each of the members of the
pair will act on one side of the door-stile.
Bits formed as above described can be used 50
with, against, or across the grain.

Having thus fully described my invention,
what I claim as new, and desire to secure by
Letters Patent, is—

1. A bit of the kind described comprising a 55
flat body portion having parallel, integral,
rearwardly-extending shanks, a forwardly-
projecting beveled prong in alinement with
one of the shanks, and an upwardly and out-
wardly curved cutting-blade integral with one 60
side of the body portion and coextensive with
a portion of the prong.

2. A bit of the kind described comprising a
flat body portion having parallel, rearwardly-
extending shanks, a forwardly-projecting 65
prong in alinement with one of the shanks,
the forward end of said prong being beveled
to form a straight cutting edge, and a com-
pound curved cutting-blade extending up-
wardly and laterally from the side of the body 70
portion adjacent the prong.

HANFORD R. MILES.
